P. GROEBER.

WALL PAPER.

No. 15,242.

Patented Aug. 12, 1884.

UNITED STATES PATENT OFFICE.

PAUL GROEBER, OF NEW YORK, N. Y.

DESIGN FOR WALL-PAPER.

SPECIFICATION forming part of Design No. 15,242, dated August 12, 1884.

Application filed April 11, 1884. Term of patent 3½ years.

To all whom it may concern:

Be it known that I, PAUL GROEBER, a citizen of the United States, residing in the city of New York, county and State of New York, 5 have invented and produced a new and original Design for Wall or Ceiling Covering, which is especially intended as a ceiling-filling.

The drawing represents a front plan view of the design.

10 The design consists of a number of radiating shell-like forms, *a*, circular in form, having escalloped edges. They are placed at irregular distances, and completely fill the field of the

design. The shell-like forms are also of uneven diameter and overlap each other. In 15 some instances a second and a third marginal escalloped edge is shown.

I claim—

The design for a wall or ceiling covering, shown in the print accompanying this description. 20

PAUL GROEBER.
